UNITED STATES PATENT OFFICE

171,831

COMBINED TOY BLOWPIPE AND TARGET OR SIMILAR ARTICLE

Irving Savran, Brooklyn, N. Y.

Application April 16, 1953, Serial No. 24,529

Term of patent 3½ years

(Cl. D34—15)

To all whom it may concern:

Be it known that I, Irving Savran, a citizen of the United States and a resident of Brooklyn, county of Queens, State of New York, have invented a new, original, and ornamental Design for a Combined Toy Blowpipe and Target or Similar Article, of which the following is a specification, reference being had to the accompanying drawings, forming part hereof, and in which:

Fig. 1 is a top plan view of a combined toy blowpipe and target or similar article, showing my new design;

Fig. 2 is a side elevational view thereof;

Fig. 3 is an end elevational view thereof; looking at the left end in Fig. 2; and

Fig. 4 is an end elevational view thereof, looking at the right end in Fig. 2.

I claim:

The ornamental design for a combined toy blowpipe and target or similar article, substantially as shown.

IRVING SAVRAN.
